UNITED STATES PATENT OFFICE.

JOSEPH A. HORNE, OF STAMFORD, CONNECTICUT, ASSIGNOR TO THE YALE & TOWNE MANUFACTURING COMPANY, OF STAMFORD, CONNECTICUT.

COIN-CONTROLLED LOCK.

1,055,178.

Specification of Letters Patent. Patented Mar. 4, 1913.

Application filed July 17, 1909. Serial No. 508,240.

To all whom it may concern:

Be it known that I, JOSEPH A. HORNE, of Stamford, in the county of Fairfield and State of Connecticut, have invented certain new and useful Improvements in Coin-Controlled Locks; and I do hereby declare the following to be a full, clear, and exact description of the invention, such as will enable others skilled in the art to which it 10 appertains to make and use the same.

My invention relates to an improvement in coin controlled locks, the object of the invention being to provide a coin controlled lock for lockers and other receptacles in 15 public places, the construction being such that a person, by inserting the proper coin, can purchase the use of the locker, and when he returns with the proper key, can open the locker and regain his property 20 stored therein, whereupon the key will be trapped in the lock and cannot be turned for locking the door, or be removed until another coin is inserted and the operation repeated.

25 With this object in view my invention consists in a trapping lever connected to the bolt and resting in the path of movement of the coin, whereby the weight of the coin moves the trapping lever to a position to release the bolt thus permitting the key to be turned to a position to project the bolt and to be withdrawn from the lock.

30 My invention further consists in the parts and combination of parts and in the details 35 of construction as will be more fully explained and pointed out in the claims.

In the accompanying drawings, Figure 1 is a view in elevation of the lock showing the bolt retracted. Fig. 2 is a similar view 40 with the bolt projected, and Figs. 3 and 4 are similar views with the face plate of the lock removed.

1 represents a lock; 2 the bolt, the shank of which is slotted as shown; 3 the key plug 45 mounted at its ends in the lock case, and provided with a groove for the reception and passage of the key 4, and 5 are the tumblers pivotally mounted on the post 6 and adapted to engage the fence 7 on the bolt 50 and hold the latter in its projected position.

By turning the key, the tumblers will be moved until the gates therein align with the fence on the bolt, thus permitting the latter 55 to be retracted by the continued movement

The parts above referred to may be of any well known and approved forms of locks now in common use.

8 is the trapping lever pivotally secured to the rear end of the bolt, and projecting 60 outwardly through the slot 9 in the rear end of the lock case. This lever 8 is provided with a shoulder 10, which, when the bolt is retracted, projects outside of the lock case, and is held up against the wall of the slot 65 in the lock case by the spring 11, carried by the shank of the bolt and engaging the lever. The rear end of this lever, when the bolt is retracted, rests within, or adjacent to a coin chute 12, and in the path of movement 70 of the coin passing through said chute, so that the weight of the coin comes in contact with the upper edge of the trapping lever 8, and by depressing same frees the shoulder 10 from its engagement with the 75 lock case, thus freeing the bolt, and permitting it to be projected by its key.

The escutcheon 13 is provided with a lip 14, having a slot 15 which alines with the groove in the key plug, when the bolt is 80 projected. The key is slotted as at 16 for the entrance of the lip 14, hence it will be seen that the key cannot be removed from the lock, except when the bolt is in its projected position. When the bolt is retracted 85 the key will be trapped, and so held until the bolt has been released by the deposit of a proper coin into the coin chute.

The weight of the coin, resting on the trapping lever disengages the shoulder on 90 the lever from the lock case, thus freeing the bolt and permitting it to be projected by its key. After the bolt has been projected, the key may then be removed. The projection of the bolt carries the trapping lever 95 from under the coin, thus releasing the latter and permitting it to fall into the coin receptacle. By again inserting the key and turning it to the right, the bolt will be retracted, and it and the key will both be 100 trapped by the engagement of the lever with the lock casing, until again released by the proper coin.

The coin chute 12 is shown in the present instance as attached to the lock casing. It 105 may however be attached to any convenient part of the locker or other receptacle to which the lock may be applied, but must, of course, be so located with relation to the trapping lever, that, when the bolt is re- 110

tracted, the outer free end of the lever will obstruct the chute and prevent the passage of a coin through the same. The coin rests on the trapping lever until the bolt is moved 5 to its projected position by the key. As the bolt moves forwardly, the trapping lever will be moved in the same direction, and out of the passage in the coin chute, thus permitting the coin to drop into the coin re- 10 ceptacle.

As the weight of the coin is removed from the lever, the spring moves the latter to its normal position, so that when the bolt is again retracted, the trapping lever will engage the lock case and absolutely prevent a second projection of the bolt until the lever has been again released by a coin falling and resting thereon.

It is evident that many slight changes 20 might be resorted to in the relative arrangement of parts shown and described without departing from the spirit and scope of my invention hence I would have it understood that I do not wish to confine myself to the 25 exact construction and arrangement of parts shown and described, but,

Having fully described my invention what I claim as new and desire to secure by Letters-Patent, is:—

30 1. In a coin controlled lock, the combination with a bolt and a key for actuating same, the escutcheon and key having engaging parts whereby the key can be inserted in, or removed from the lock, only when the 35 bolt is in its projected position, of a pivoted trapping lever movable longitudinally with the bolt and adapted when the bolt is retracted, to engage a stop and lock the bolt in

its retracted position, and a coin chute which is obstructed by the trapping lever when the 40 bolt is retracted.

2. In a coin controlled lock, the combination with a bolt, a key for actuating same, the escutcheon and key having engaging parts whereby the key can be inserted in, or 45 removed from the lock, only when the bolt is in its projected position, and a coin chute, of a trapping lever pivoted to the bolt and adapted when the bolt is retracted, to engage a stop and lock the bolt in its retracted position and also obstruct the passage through the coin chute, whereby the weight of a coin deposited in the chute disengages the lever from its stop and permits the bolt to be projected by the key.

3. In a coin controlled lock, the combination with a bolt, a key for actuating same, and means for preventing the removal of the key from the lock except when the bolt is projected, of a coin chute, a trapping lever pivoted to the bolt and provided with a shoulder adapted to engage a stop when the bolt is retracted and lock the bolt against the action of the key, the said trapping lever resting in the path of a coin in the coin chute when the bolt is retracted, and a spring normally tending to hold the shoulder on the lever in contact with the stop.

In testimony whereof, I have signed this specification in the presence of two subscribing witnesses.

JOSEPH A. HORNE.
